[57] CLAIM

The ornamental design for a corner unit for a kitchen countertop, as shown.

DESCRIPTION

FIG. 1 is a perspective view of a corner unit for a kitchen countertop showing my new design;

FIG. 2 is a top plan view thereof;

FIG. 3 is a bottom view thereof;

FIG. 4 is a side elevational view looking in the direction of the arrows 4—4 of FIG. 2;

FIG. 5 is a side elevational view looking in the direction of the arrows 5—5 of FIG. 2;

FIG. 6 is a front elevational view looking in the direction of the arrows 6—6 of FIG. 1;

FIG. 7 is a side elevational view looking in the direction of the arrows 7—7 of FIG. 2;

FIG. 8 is a side elevational view looking in the direction of the arrows 8—8 of FIG. 2;

FIG. 9 is a perspective view corresponding to FIG. 1 showing a modified form of my invention; and,

FIG. 10 is a perspective view corresponding to FIG. 1 showing another modified form of my invention.
